EXPANSIBLE LINK CHAIN FOR A WRIST WATCH BRACELET OR THE LIKE

William C. Boots, Rumford, R. I., assignor to Foster Metal Products Incorporated, Attleboro, Mass., a corporation of Massachusetts

Application April 8, 1953, Serial No. 24,413

Term of patent 14 years

(Cl. D45—4)

To all whom it may concern:

Be it known that I, William C. Boots, a citizen of the United States, residing at Rumford, in the county of Providence and State of Rhode Island, have invented a new, original, and ornamental Design for an Expansible Link Chain for a Wrist Watch Bracelet or the like, of which the following is a specification, reference being had to the accompanying drawing, forming a part hereof, in which:

Fig. 1 is a top plan view of an expansible link chain for a wrist watch bracelet or the like, showing my new design;

Fig. 2 is a top plan view thereof shown in an expanded condition with portions of the conventional bottom links being visible between the top links and shown in broken lines; and

Fig. 3 is a perspective view of one of the top links thereof drawn on an enlarged scale.

The bottom links, shown in Fig. 2 in broken lines, may be conventional and form no part of my ornamental design.

I claim:

The ornamental design for an expansible link chain for a wrist watch bracelet or the like, substantially as shown and described.

WILLIAM C. BOOTS.
